DESIGN FOR A RANGE

Donald L. Hadley, Forest Hills, Pa., assignor to
Westinghouse Electric & Manufacturing Com-
pany, a corporation of Pennsylvania

Application September 15, 1939, Serial No. 87,237

Term of patent 7 years

To all whom it may concern:

Be it known that I, Donald L. Hadley, a citizen of the United States, residing at Forest Hills, in the county of Allegheny and State of Pennsylvania, have invented a new, original, and ornamental Design for a Range, of which the following is a specification, reference being had to the accompanying drawing, forming part thereof, in which:

Figure 1 is a perspective view, taken from the

front and one side of the range, showing my new design;

Fig. 2 is a top plan view of my range; and

Fig. 3 is an elevational view, taken from the side that is remote in the perspective view of Fig. 1, of my range.

I claim:

The ornamental design for a range, substantially as shown.

DONALD L. HADLEY.
